UNITED STATES PATENT OFFICE.

EPHRAIM JAQUES, OF GENESEO, ILLINOIS.

PAPER-WEIGHT AND SPONGE-CUP.

SPECIFICATION forming part of Letters Patent No. 592,145, dated October 19, 1897.

Application filed February 3, 1897. Serial No. 621,833. (No model.)

To all whom it may concern:

Be it known that I, EPHRAIM JAQUES, of Geneseo, in the county of Henry and State of Illinois, have invented a new and Improved 5 Paper-Weight and Sponge-Cup, of which the following is a full, clear, and exact description.

The object of the invention is to provide an article particularly adapted for use as a part 10 of desk furniture, and in which will be combined a paper-weight and a sponge-holder, the article being also capable of being used for moistening the fingers, moistening stamps, or for any object requiring the application of a 15 liquid.

A further object of the invention is to provide a reservoir for liquid connected with the body of the article, said reservoir being compressible and so arranged that the liquid contained 20 therein may be supplied in predetermined quantities to a receptacle in the body of the article, the surplus fluid being withdrawn from this receptacle when the reservoir is relieved from pressure.

25 A further object of the invention is to provide a paper-weight and sponge-cup, or a paper-weight having a receptacle to which the liquid is supplied, the article being simple, durable, and economic, and the liquid so controlled that it will not spill from the article should it be overturned.

The invention consists in the novel construction and combination of the several parts, as will be hereinafter fully set forth, 30 and pointed out in the claims.

Reference is to be had to the accompanying drawings, forming a part of this specification, in which similar characters of reference indicate corresponding parts in all the figures.

40 Figure 1 is a side elevation of the device. Fig. 2 is a plan view thereof, and Fig. 3 is a longitudinal vertical section taken substantially on the line 3 3 of Fig. 2.

The body A of the device is made of glass, 45 celluloid, metal, or any desired material, and may be given any suitable contour. The body of the device is to be primarily used as a paper-weight, and in the top of the body a chamber 10 is formed, adapted as a receptacle for water or other liquid used for moistening 50 purposes. An opening 11 is made in the bot-

tom of the chamber or receptacle 10, which opening is in communication with a channel 12. The channel is carried in direction of the outer face of the body, and terminates in an 55 enlarged portion 13, the enlargement being substantially pear-shaped. The enlargement may, however, be given other contour, and adjacent to the enlarged outer end 13 of the channel 12 a cavity or recess 14 is preferably 60 made in the outer face of the body.

In connection with the body a hollow sphere 15 or a bulb is employed, constructed of rubber or a like material. This hollow sphere or bulb is provided with a shank 16, enlarged 65 between its ends, the enlargement of the shank corresponding in shape to the contour of the enlarged portion 13 of the channel 12, in which it is to enter. The enlarged channel portion 13, however, is of less dimensions than 70 the normal dimensions of the shank 16. The outer end of the shank is open and its inner end communicates with the interior of the hollow sphere or bulb 15. The shank 16 of the bulb 15 is introduced into the enlarged 75 portion 13 of the channel 12, the outer face of the bulb adjacent to the shank fitting to the wall of the recess 14 in the body. Water may be supplied in any desired quantities to the receptacle 10 by simply pressing the bulb 80 or hollow sphere 15, and the water may be utilized to moisten a sponge, to dampen the finger, or for any suitable purpose. The bulb may be filled with water after its removal or 85 may be supplied, and preferably is supplied, by placing water in the chamber 10 and compressing and releasing the bulb.

In operation when the bulb or sphere is released from pressure the expansion of the bulb will draw into the same any surplus water that may be in the receptacle, thereby 90 preventing the spilling of the water in the event the device should be overturned.

This invention will be specially useful to school-children, as affording a ready means 95 of cleaning their slates, and to dressmakers or tailors for moistening seams before pressing.

Having thus described my invention, I claim as new and desire to secure by Letters Patent—

1. A paper-weight or like article, provided 100 with a chamber in its upper face, a channel

- connected with the bottom of said chamber, having an enlargement at its outer end, and a bulb adapted to contain liquid and constructed of an elastic material, said bulb being provided with a shank arranged to enter the enlargement at the outer end of said channel and to fill the space at said enlargement, as and for the purpose specified.
2. A sponge-holder having a rigid base with a concavity in its upper side forming a cup to receive the sponge, the base having a passage run laterally from the bottom of the concavity, and a compressible bulb in communication with the passage.
3. A sponge-holder having a rigid body portion with a concavity in its upper face, the concavity forming a cup for the sponge, and the body portion having a horizontally-extending passage run from the central lower portion of the concavity to one side of the body portion, and a compressible bulb in com-

munication with said passage and held at the said one side of the body portion.

4. A sponge-holder having a rigid base with a concavity in the upper side, the concavity forming a cup for the sponge and the body portion having a passage run from the concavity to one side of the body portion, and a compressible bulb communicating with the passage and held at the said one side of the body portion.

5. A sponge-holder having a rigid body portion with a concavity in its upper face, the concavity forming a cup for receiving the sponge, and a compressible bulb held at one side of the body portion and having communication with the concavity.

EPIRAIM JAQUES.
